(57) CLAIM

I claim the ornamental design for a sole for footwear, as shown and described.

DESCRIPTION

FIG. 1 is a bottom plan view of the sole for footwear showing my new design;

FIG. 2 is a right side elevational view thereof, the left side being a mirror image;

FIG. 3 is a front elevational view thereof; and,

FIG. 4 is a rear elevational view thereof.

The broken lines showing a portion of the top view form no part of the claimed design.
